Primary Examiner — Cynthia M. Chin**CLAIM**

We claim the ornamental design for a toe cap for a skate, as shown and described.

DESCRIPTION

FIG. 1 is a perspective view of a toe cap for a skate according to the design;

FIG. 2 is a front elevational view of the toe cap of FIG. 1; FIG. 3 is a rear elevational view of the toe cap of FIG. 1; FIG. 4 is a top plan view of the toe cap of FIG. 1; FIG. 5 is a bottom plan view of the toe cap of FIG. 1; FIG. 6 is a left side elevational view of the toe cap of FIG. 1;

FIG. 7 is a right side elevational view of the toe cap of FIG. 1; and,

FIG. 8 is a perspective view of the toe cap of FIG. 1 in its environment.

The broken lines shown are included for the purpose of illustrating portions of the article which are not part of the claimed design.
